UNITED STATES PATENT OFFICE.

JACOB MURSET, OF BROOKLYN, NEW YORK.

WATCHCASE CONSTRUCTION.

1,152,537.

Specification of Letters Patent. Patented Sept. 7, 1915.

Application filed March 16, 1915. Serial No. 14,634.

To all whom it may concern:

Be it known that I, JACOB MURSET, a citizen of the United States, and residing at Brooklyn, in the county of Kings and State 5 of New York, have invented certain new and useful Improvements in Watchcase Constructions, of which the following is a specification, such as will enable those skilled in the art to which it appertains to 10 make and use the same.

This invention relates to the construction of watch cases and particularly to the cases of hunting watches, and still more particularly to means for opening and closing one 15 side of said cases, and the object thereof is to provide the rim of the case of a watch of the class specified with an improved spring construction operated by the winding stem of the watch which is movable inwardly and outwardly to open the front of the 20 case and by which the said front of the case is also held in a closed position; and with this and other objects in view the invention consists in the construction, combination and arrangement of parts hereinafter described and claimed.

The invention is fully disclosed in the following specification, of which the accompanying drawing forms a part, in which the 30 separate parts of my improvement are designated by suitable reference characters in each of the views, and in which:—

Figure 1 is a sectional side view of a watch case provided with my improvement and showing the front side in an open position; Fig. 2 a section on the line 2—2 of Fig. 1; Figs. 3 and 4, side views respectively of two separate spring metal blanks which I employ; and, Figs. 5 and 6 are side 40 views respectively of springs made from the blanks shown in Figs. 3 and 4.

In the drawing forming part of this specification, I have shown at *a* the rim of what is ordinarily called a hunter's case watch 45 and the hinged front side of which is shown at *b*. The front side *b* of the case is hinged at *b*² and the rim *a* is channeled on its inner side, or provided with a deep annular groove *a*² and at *c* I have shown the winding post 50 which is movable inwardly and outwardly through an aperture in the rim *a* at *a*³. The winding post *c* is provided inwardly of the rim *a* with a collar *c*² and the inner end *c*³ of said winding post extends inwardly a 55 predetermined distance from said collar, and

in the practice of my invention, I provide two curved spring devices *d* and *e* shown in Figs. 5 and 6, and which are placed in the opposite side portions of the rim *a*, and which are formed respectively from the 60 blanks shown at *d*² and *e*² in Figs. 3 and 4. The end portion *d*³ of the blank *d*² is wider than the other end portion *d*⁴ thereof, in the construction shown, and the end portion *d*³ is provided with a longitudinally ex- 65 tended tongue *d*⁵, while the end portion *d*⁴ is provided with a laterally directed tongue *d*⁶. The end portion *e*³ of the blank *e*² is wider than the end portion *e*⁴ of said blank and is provided with a longitudinally ex- 70 tended tongue *e*⁵, while the end portion *e*⁴ of said blank is provided with a longitudinal reduced extension *e*⁶ having a laterally directed tongue *e*⁷.

My invention, however, is not limited to 75 the exact shape or form of the blanks *d*² and *e*² and the object thereof, as shown and described, is to enable the wider end portions *d*³ and *e*³ of said blanks to hold the spring devices *d* and *e* more securely in the annular 80 groove *a*² of the rim *a*, and to give the end portion *d*⁴ of one blank and the end portion *e*⁴—*e*⁶ of the other greater elasticity and at the same time reduce the strength of the end portion *e*⁴—*e*⁶ of the blank *e*². The springs 85 *d* and *e* are formed by folding the blanks *d*² and *e*², as shown in Figs. 5 and 6, the larger end portion being folded upon the body portion so that the end portions *d*⁴ and *e*⁴ project as shown. The springs *d* and *e* are 90 placed in the opposite sides of the rim *a* in reversed position, and the larger end portions thereof, or the tongue members *d*⁵ and *e*⁵ are formed into loops *f* through which are passed pins *f*² which secure said springs 95 in the rim. The winding post *c* passes loosely through the end of the part *d*⁴ of the spring *d* and the tongue *d*⁶ thereof is formed into a hook-shaped catch *d*⁷ which catches and holds the side *b* of the casing when said side 100 is swung into a closed position, as clearly indicated in dotted lines in Fig. 2.

When the springs *d* and *e* are secured in position, in the manner shown, the reduced or free end *e*⁶ of the spring *e* is just within 105 the hinged point of the side *b* of the case, and the tongue *e*⁷ of the spring *e* is bent as shown at *e*⁸ in Figs. 1 and 2 to form a finger which bears on the side *b* of the case just 110 outwardly of the hinge *b*² and, by reason of

this construction, said spring *e* operates to open the front side case member *b* when the winding post *c* is forced inwardly, and said side front member of the case is released 5 from the spring *d*, or the hook-shaped member *d'* thereof by the forcing of the winding post inwardly and the spring *e*, or the part *e'* thereof holds the front case member *b* in an open position until said front case member *b* is forced into the closed position by 10 hand. The outer end of the winding post *c* passes outwardly through a tubular neck *g* connected with the arm *a* and is provided with the usual knob or head by which said post is manipulated, but as this forms no 15 part of my invention said knob or head is not shown.

My invention is not limited to the exact 20 shape or form of the blanks *d²* and *e²* from which the springs *d* and *e* are made, as herein described, nor is it limited to the exact 25 form of the said springs *d* and *e*, and various changes in and modifications of the details of my improvement herein shown and described may be made, within the scope of the appended claim, without departing from the spirit of my invention or sacrificing its advantages.

Having fully described my invention, what

I claim and desire to secure by Letters Patent, is:—

In a watch case, a rim provided at one side with a hinged side member and at the opposite side with a radially movable winding post, spring devices countersunk in opposite 35 side portions of the rim and one of which serves to lock the hinged side case member in a closed position and the other to force said hinged side case member open when the lock is released and said lock being released 40 by the inward movement of the winding post, said spring devices being formed from strips of metal bent to form parallel parts one of which is longer than the other, and the shorter parts being free from the longer 45 parts at their ends and being provided with loops through which are passed pins by which said spring devices are secured to the case, and the longer parts being free from the case throughout their lengths. 50

In testimony that I claim the foregoing as my invention I have signed my name in presence of the subscribing witnesses this 13th day of March, 1915.

JACOB MURSET.
